UNITED STATES PATENT OFFICE.

BENJAMIN F. MAYO, OF SALEM, MASSACHUSETTS, ASSIGNOR TO THE MCKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,837, dated May 23, 1899.

Application filed April 26, 1899. Serial No. 714,592. Term of patent 14 years.

To all whom it may concern:

Be it known that I, BENJAMIN F. MAYO, a citizen of the United States, residing at Salem, in the county of Essex and Commonwealth of Massachusetts, have invented and produced a new and original Design for a Protective Slug, of which the following is a specification.

Figure 1 is an end view of a protective slug, illustrating my design; and Fig. 2 is an end elevation thereof viewed from the open end of the wings.

The leading feature of my design for a protective slug consists of an elongated body bent transversely between its ends at two places to form a central portion with extended oppositely-inclined straight wings.

The protective slug comprises an elongated body bent transversely at two places at a a' between its ends to leave a central portion a^2 with extended angular straight wings a^3 a^4 , ²⁰ the wings being inclined in different directions from said central portion.

Having fully described my design, what I claim, and desire to secure by Letters Patent, is—

The design for a protective slug, substantially as herein shown and described.

In testimony whereof I have signed my name to this specification in the presence of two subscribing witnesses.

BENJAMIN F. MAYO.
